PAPER FEEDING MECHANISM

Diedrich Friedrich Schumacher, Berlin-Britz,
Germany, assignor, by mesne assignments, to
International Business Machines Corporation,
New York, N. Y., a corporation of New York

Application June 13, 1928, Serial No. 285,007, and
in Germany January 23, 1928

18 Claims. (Cl. 235—58)

This invention concerns accounting machines and has more particular relation to improvements in the line-spacing devices for the paper strip receiving the items and totals thereof.

5 It is a broad object of the present invention to provide improved and simplified means whereby an extra line spacing operation occurs upon a change in the group classification of items. It is a further object of the present invention 10 to provide improved and simplified means whereby the items and the total of a group of items appear together and to further differentiate the total printed from the next group of items printed by effecting an extra line spacing operation after 15 a total printing operation.

More specifically it is an object of the present invention to provide improved and simplified means whereby a line spacing operation of the paper occurs in addition to that preceding the 20 printing of the total whereby a blank space separates the total from the next item to be printed.

In carrying out the present invention duplicate paper feeding devices are provided, one normally functioning upon each item listing operation. 25 The supplemental paper feeding device is normally inoperative but functions at the initiation of the total printing cycle and again at the termination of the total printing cycle, after which time the paper is given a step of movement by the regular paper feeding devices to receive the first item of the next group of items. The extra line spacing movement provides a blank space which separates the total printed from the first item of a succeeding group.

35 Referring to the drawing wherein there is shown what is considered to be the preferred form of the invention:

Fig. 1 is a perspective diagrammatic view of the card feeding and line spacing devices comprising a single embodiment of the present invention;

Fig. 2 illustrates some of the parts shown in Fig. 1 in the normal or "D" position of the tabulator and showing a certain member unlatched 45 and in readiness to fall urged by its related spring;

Fig. 3 is a concrete example of a record strip printed by the present machine.

Figs. 4-7 are different views in side elevation 50 which disclose the configuration of a particular cam and its relation to a certain member.

In the drawing, reference character 10 designates a constantly rotating shaft of the tabulating machine to which is fixed one element 11

of a clutch, the associated element 12 of which is splined to a card feeding shaft 13. The gear train 14 is driven by shaft 13 and is commonly used in tabulating machines for feeding cards to analyzing brushes by feeding rollers 15. In addition, one of the gears 14 reciprocates a connecting rod 16 which is similar to that ordinarily used in tabulators for drawing cards singly from a stack 17 into the machine by the usual picker 18, where they are engaged by the feed rollers 15, cards being fed as long as the clutch connection is established.

As the cards are fed to the analyzing brushes the perforations are sensed and the items represented thereby are transposed to the registering mechanism as well as to the printing devices. Prior to each printing operation it is desirable, of course, to space the sheet to prevent overprinting. The preferred mechanism for effecting spacing of the paper comprises a pair of ratchet 75 wheels 19 and 20 carried by the shaft 21 which supports the platen roller 22 around which the paper strip 23 is partially wound. Associated with ratchet wheel 19 is an actuating lever 24 having a tooth 25 adapted to be retained in operative engagement with the ratchet wheel teeth by a spring 27. When the actuating lever 24 is raised by a cam 28 on shaft 13 the tooth 25 of the lever 24 slips idly over the ratchet wheel 19 without effecting any movement of the platen roller 80 22. However, when lever 24 is restored by a spring 29, occasioned by the roller 30 of lever 24 dropping off the high point of the cam 28, the lever 24 will partially rotate the ratchet wheel 19, shaft 21 and platen 22 to space the paper after 85 which the item is printed. This operation ensues upon each card feeding cycle so that as each item represented by a card is printed it is suitably spaced from the preceding item.

Cooperatively associated with the ratchet 95 wheel 20 in a similar manner is an actuating lever 31 but it will be observed that during item printing operations its roller 32 is normally (see Fig. 4) held out of engagement with a cam 33 also driven by the card feeding shaft 13. This 100 relation is effected by the latching of an arm 34 fixed to a shaft 35 which shaft carries at its end an arm 36 articulated to the lower end of lever 31. The latching relationship just referred to is preferably effected by an arm 37 which is urged by a spring 37a to normally abut the clutch element 12, the arm 37 having its upper end under the free extremity of arm 34.

Tabulating machines are ordinarily equipped with control mechanism whereby a total is auto- 110

matically printed after the last card of a group of cards of like classification is tabulated. It will be observed then, that as long as the successive cards are of the same classification or group control number, the machine continues listing of items. When a card having a different group control number is presented to the analyzing brushes certain mechanism comes into play to cause stoppage of the feeding of cards and the setting up of the total taking devices of the machine to take a total of the items that have been accumulated from the cards of the previous group, all as explained in the patent to Lake 1,600,413.

15 It is desirable, of course, that in order to readily identify the total with the group of related items it be suitably spaced by a blank space from the next item and, in the present instance, this is accomplished by the mechanism described as follows:

When card groups change, the feeding of cards is discontinued and in the present instance; this is effected by a controlling member 38, the upper end of which has a suitable connection to clutch element 12 and which member is shifted to the left (Fig. 2) by any suitable electrical or mechanical means whenever card groups change. In the shifted position of member 38, shaft 13 is disconnected from driving shaft 10. As clutch element 12 is shifted, latching arm 37 will be rocked, disengaging its upper end from the free extremity of arm 34 whereupon spring 39 will draw the actuating lever 31 downwardly until roller 32 strikes the point 40' of cam 33 (see Fig. 5) to cause a partial rotation of shaft 21 and platen roller 22, immediately spacing the paper so that the total to be subsequently printed will be printed in the space provided by the operation just described and immediately under the last item of

40 the group.

The total printing cycle occurs during the time shafts 10 and 13 are unclutched at which time no card feeding operation takes place. At the termination of the total printing cycle shafts 10 and 13 are subsequently clutched by the reverse shifting of the member 38. However, arm 37 does not follow the movement of clutch element 12 as it is prevented by the engagement of said arm with the arm 34 which is still in its lowered position. Upon a partial rotation of the shaft 13 synchronous with the initiation of the next card feeding cycle roller 32 will drop off the point 40' of cam 33 (see Fig. 6) partially rotating ratchet wheel 20 to suitably blank space the printed total from the first of the items pertaining to the next group of cards.

At some point during the first card cycle a projection 40 or the highest point of the cam 33 will engage roller 32 rocking shaft 35 to enable arm 37 to be urged by spring 37a to a position abutting clutch element 12 but with its upper extremity beneath the arm 34 to re-latch arm 34 in its normal elevated position (see Fig. 7). At substantially the termination of the first card cycle, cam 28 will effect a line spacing movement of the paper which space will be taken up by the item represented by the first card fed. Subsequent card feeding operations will then ensue, the items being printed one after the other until the card group changes whereupon the cycle of events just described will be repeated until all the cards have been tabulated.

What is claimed is as follows:

1. In a machine of the class described including means for normally effecting line spacing op-

erations of a record sheet during successive item printing operations, a normally latched supplemental paper feeding device, and means whereby the unlatching of the supplemental paper feeding device effects an additional line spacing operation.

2. A machine of the class described comprising separate trains of mechanism for effecting paper feeding operations, a common driving shaft therefor, one of said trains having an inoperative relationship with the driving shaft, and means whereby a paper feed operation occurs prior to establishing an operative relationship between the last mentioned train and the driving shaft.

3. A machine of the class described including means for effecting line spacing operations of a record sheet during successive item printing operations, a supplemental paper feeding device for effecting an additional line spacing operation, driving means therefor comprising a cam and means for preliminarily feeding the record strip prior to establishing a cooperative relationship between the supplemental paper feeding device and said cam.

4. A machine of the class described comprising separate trains of mechanism for effecting line spacing operations of a record sheet one of said trains being normally ineffective, a common shaft therefor and means whereby the ineffective train is rendered operable in a plurality of successive steps of operation, one of said steps occurring prior to establishing an operative relationship between the ineffective train and said shaft.

5. A machine of the class described comprising in combination a platen, means for effecting line spacing operations of a record sheet by operating the platen during listing operations and supplemental means for effecting line spacing operations ineffective during listing operations both of said means being operated by a common power shaft and said supplemental means effecting an operation of the platen to effect a line spacing operation of an additional extent as an incident to total taking operations.

6. A record controlled tabulator, including a shaft for driving the card feeding mechanism and listing mechanism, a paper spacing device comprising means operated by the shaft for effecting paper spacing in predetermined increments during listing operations and means adjusted by the shaft for effecting extra paper spacing both at the beginning and at the end of a listing run.

7. In a machine of the class described, in combination, a shaft operated during listing operations, means operated thereby for effecting a line spacing operation during each listing operation, a supplemental line spacing means and means whereby the latter is set for operation by said shaft and subsequently operable to effect an additional line spacing operation.

8. In a machine of the class described, in combination, a normally latched line spacing device, a device operable during total taking operations, means whereby said device unlatches the line spacing device, and means whereby the line unlatching of the line spacing device effects the line spacing operation.

9. In a machine of the class described, in combination, means for feeding a record strip during item listing operations, separate means for feeding the record strip an additional amount to separate the last of a group of items from the

following printed total, a common power shaft for operating both feeding means, and means whereby said power shaft causes the operation of the last named feeding means whereby the latter is operable to effect successive record strip feeding operations while the first named feeding means is ineffective to accomplish a record strip feeding operation.

10. In a machine of the class described, in combination, a line spacing device operated during each listing operation, a supplemental line spacing device, means whereby the latter is set for operation during a listing operation, and means operable during a total taking operation for causing the supplemental device to operate.

11. In a machine of the class described, in combination, a line spacing device operated during each listing operation, a supplemental line spacing device, means whereby the supplemental line spacing device is set for operation, during a listing operation and means whereby the latter is subsequently effective in a plurality of steps of operation.

12. A record controlled machine having a card feeding mechanism operable during item listing operations controlled by classified record cards, in combination with a line spacing device operated for each item listing operation, a supplemental line spacing device, and means whereby the latter device is set for operation during the first listing operation which follows a change in classification of record cards.

13. In a machine of the class described the combination with a platen, of a train of mechanism for effecting line spacing operations of a record sheet during item printing operations by operating the platen, means comprising a separate train of mechanism for operating the platen to effect an additional line spacing of the record sheet when a total is printed, and a rotatable driving shaft of the machine for both trains of mechanism.

14. In a machine of the class described the combination with a platen, a train of mechanism for effecting line spacing operations of a record sheet by operating the platen during item printing operations, means comprising a separate train of mechanism for operating the platen to effect an

additional line spacing of the record when a total is printed, a rotatable shaft, and means whereby said shaft in its rotation controls the operation of both of said spacing mechanisms in an alternating sequence.

15. In a machine of the class described the combination with a train of mechanism for effecting line spacing operations of a record sheet, of means comprising a separate train of mechanism for effecting an additional spacing of the record sheet when a total is printed, a drive shaft of the machine common to both of said mechanisms, and means whereby said shaft in its rotation causes the last named means to be effective after a total is printed while the first mentioned train of mechanism is ineffective to accomplish a line spacing operation.

16. In a machine of the class described the combination with a device for effecting line spacing operations of a record sheet during successive item printing operations, of a normally latched device for effecting an additional line spacing operation, means for latching said device, means whereby the unlatching of the additional line spacing device effects a line spacing operation and means for displacing the latching means to unlatch the additional line spacing device when a total is to be printed on the sheet.

17. In a record controlled machine, the combination with a shaft for driving the card feeding mechanism, of a paper spacing device operated by the shaft for spacing the paper when listing items from the cards, a supplemental paper feeding device and means for operating it, and means operated by the shaft during a listing operation for adjusting said supplemental paper feeding device in position to be operated by its operating means.

18. In a record controlled machine, the combination with a shaft for driving the card feeding mechanism, of a spacing device driven by said shaft for separating the items represented by the cards, and means driven by said shaft during a listing operation for causing an additional paper spacing operation after a total has been printed.

DIEDRICH FRIEDRICH SCHUMACHER.
